CLAIM

The ornamental design for an inflatable slide, as shown and described.

DESCRIPTION

The patent or application file contains at least one drawing executed in color. Copies of this patent or patent application publication with color drawings will be provided by the Office upon request and payment of the necessary fee.

FIG. 1 is a front and right side perspective view of the inflatable slide, showing my new design;

FIG. 2 is a front and left side perspective view thereof;

FIG. 3 is a right side and top perspective view thereof;

FIG. 4 is a left side and top perspective view thereof; and,

FIG. 5 is a detail of the front and right side perspective view thereof.

The broken line showing of the pump on FIG. 4 is included for the purpose of illustrating unclaimed subject matter and forms no part of the claimed design.

1 Claim, 5 Drawing Sheets
(5 of 5 Drawing Sheet(s) Filed in Color)
